US0D1100121S

(12) **United States Design Patent** (10) **Patent No.:** **US D1,100,121 S**
(45) **Date of Patent:** **** Oct. 28, 2025**

(54) **FISHING ROD HOLDER**

(71) Applicant: **Jiangmen Maimigu Trading Co. Ltd.**,
Guangdong (CN)

(72) Inventor: **BaiZhao Chen**, Guangdong (CN)

(***) Term: **15 Years**

(21) Appl. No.: **29/929,419**

(22) Filed: **Feb. 21, 2024**

(51) LOC (15) Cl. **22-05**

(52) U.S. Cl.

USPC **D22/147**

(58) **Field of Classification Search**

USPC D22/142, 147, 148, 199; 43/5, 15, 21.2

CPC A01K 97/08; A01K 97/10; A01K 91/10;

Y10S 224/922

(57) **CLAIM**

The ornamental design for a fishing rod holder, as shown and described.

DESCRIPTION

FIG. 1 is a perspective view of the fishing rod holder showing my new design;

FIG. 2 is a another perspective view of the fishing rod holder showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the figures illustrate portions that form no part of the claimed design.

1 Claim, 8 Drawing Sheets
